UNITED STATES PATENT OFFICE.

IRVING ANDERSON, OF BIRD CITY, KANSAS.

CAN OPENER.

Application filed August 26, 1927. Serial No. 215,709.

This invention relates to new and useful improvements in can openers and aims to provide a hand operated machine type of opener, principally though not specifically adapted for use in hotels, restaurants and other public places, the same being of such a nature as to facilitate the rapid cutting of the lids from the cans, and this regardless of the shape of such cans.

In carrying out the present invention there is provided a vertically reciprocating cutting element operable by hand power and beneath which the can is to be disposed, said cutter being projected through the lid of the can during the turning of the same so that the lid will be cleanly cut therefrom.

One of the most important objects of the invention is to provide a can cutting device of this character that is inexpensive of manufacture and very simple of operation, the same consisting of few parts and these so co-related as to reduce the possibility of disarrangement to a minimum.

With the foregoing and other objects in view as the nature of the invention will be better understood, the same comprises the novel form, combination and arrangement of parts hereinafter more fully described, shown in the accompanying drawings and claimed.

In the accompanying drawings forming part of this application and in which like reference characters indicate corresponding parts:

Figure 1 is a side elevation of my improved can opening device.

Figure 2 is a top plan view thereof.

Figure 3 is a fragmentary inner side elevation.

Figure 4 is a fragmentary outer side elevation, and

Figure 5 is a perspective of the lower end of the reciprocating cutter carrying bar.

Now having particular reference to the drawings, my novel can cutting device consists of a suitable base board 5 upon which is arranged transversely adjacent one end thereof an L-bar 6 to which is secured at a point intermediate the ends thereof vertically extending posts 7 upon the back side of which is arranged for rotation a train of high speed gearing 8, the uppermost large gear being equipped with a crank handle 9, while the lowermost gear is arranged upon the back end of a shaft 10 that is mounted for rotation through the post 7 and to the front end of

which is attached a relatively large fly wheel 11.

Secured to the front side of the post 7 above the uppermost gear of the high speed train 8 and extending horizontally is an arm 12 equipped at its outer end with a vertically extending flat bar guide 13 through which is mounted for vertical reciprocation a flat bar 14. Slidably arranged upon the bar 14 beneath the guide 13 is a sleeve 15 that may be secured thereto in predetermined adjusted positions by reason of a set screw 16. Pivoted to the back side of this sleeve 15 as at 17 is the upper end of a connecting rod 18, the lower end of which is eccentrically pivoted as at 19 to the front face of the fly wheel 11 and at a point but slightly offset as clearly disclosed in Figure 3.

The lower end of the reciprocating bar 14 is provided with a depending and rearwardly offset extension 14', while detachably secured to the lower end of the bar directly above the upper end of the offset portion 14' is a cutter blade 20, the side edges of which converge inwardly toward the lower end so that the same will easily pass through the lid of a can.

The invention further consists of a transversely extending bar 21 arranged upon the base 5 in front of the fly wheel 11 and against which a can A is forced when the same is disposed upon the base 5 at substantially the center thereof. In order to prevent transverse movement of the can upon the base there is provided for cooperation with the bar 21 a metallic fork 22, the apex of which is remote from the bar 21 and provided with a plate 23 formed with a longitudinal slot 24 so that the same may be adjustably secured to the base 5 by reason of a bolt and wing nut 95 connection 25.

Obviously, in actual practice the can A is arranged beneath the cutter 20 in raised condition and the can forced against the bar 21 and the offset extension 14' of the reciprocating bar 14. The screw 16 of the sleeve 15 is released so that the bar 14 may be properly adjusted so that when the bar 14 is in its fully raised position, the cutter 20 will be above the lid of the can. The screw 16 is then tightened after which the handle 9 is to be rotated for reciprocating the cutter bar 14 which will cause the rapid projection of the cutter 20 into the lid of the can A, said cutter being guided through the lid at a point adjacent the edge of the can A by the offset extension 14' of said bar 14.

Obviously if it is desired to remove the lid of a square or rectangular shaped can the fork 22 is slid out of the way and during the reciprocation of the cutter bar the can is moved transversely across the base 5 in contact with the outer edge of the guide bar 21.

In view of the foregoing description when considered in conjunction with the accompanying claims it will at once be apparent that I have provided a highly novel, simple and extremely efficient can opening device that is well adapted for all the purposes herefore designated, even though I have herein shown and described the invention as consisting of certain detailed structural elements it is nevertheless to be understood that some changes may be made therein without affecting the spirit and scope of the appended claims.

Having thus described the invention, what I claim as new is:—

1. In a can opening device of the character described, a rigidly mounted vertically extending post, a train of high speed gearing associated with the post, means whereby the gearing may be rotated, a fly wheel associated with one gear of the train, a vertically extending guide sleeve associated with the post adjacent its upper end and at the same side of the post as said fly wheel, a bar mounted for vertical reciprocatory movement through said sleeve, a cutting knife arranged upon the lower end of the bar and adapted to be engaged through the lid of a can arranged beneath said bar and a driving connection between the fly wheel and said reciprocatory bar.

2. In a can opening device of the character described, a rigidly mounted vertically extending post, a train of high speed gearing associated with the post, means whereby the gearing may be rotated, a fly wheel associated with one gear of the train, a vertically extending guide sleeve associated with the post adjacent its upper end and at the same side of the post as the fly wheel, a bar mounted for vertical reciprocatory movement through said sleeve, a cutting knife arranged upon the lower end of the bar and adapted to be engaged through the lid of a can arranged beneath said bar and a driving connection between the fly wheel and said reciprocatory

bar, and means whereby a can may be secured against lateral or longitudinal movement beneath said knife.

55

3. In a can opening device of the character described, a rigidly mounted vertically extending post, a train of high speed gearing associated with the post, means whereby the gearing may be rotated, a fly wheel associated with one gear of the train, a vertically extending guide sleeve associated with the post adjacent its upper end and at the same side of the post as the fly wheel, a bar mounted for vertical reciprocatory movement through said sleeve, a cutting knife arranged upon the lower end of the bar and adapted to be engaged through the lid of a can arranged beneath said bar and a driving connection between the fly wheel and said reciprocatory bar, means whereby a can may be secured against lateral or longitudinal movement beneath said knife, said means consisting of a bar arranged transversely beneath the knife and against which the can is to be engaged, and a clamping form arranged beneath the knife at the outer edge of said bar for engaging the opposite side of said can.

60

4. In a can opening device of the character described, a rigidly mounted vertically extending post, a train of high speed gearing associated with the post, means whereby the gearing may be rotated, a fly wheel associated with one gear of the train, a vertically extending guide sleeve associated with the post adjacent its upper end and at the same side of the post as the fly wheel, a bar mounted for vertical reciprocatory movement through said sleeve, a cutting knife arranged upon the lower end of the bar and adapted to be engaged through the lid of a can arranged beneath said bar and a driving connection between the fly wheel and said reciprocatory bar, means whereby a can may be secured against lateral or longitudinal movement beneath said knife, and an inwardly offset extension arranged upon the lower end of the bar and projecting beyond the cutting end of the knife for engagement at the outer surface of the can for guiding the knife through the top adjacent the end body.
